United States Patent

Des. 241,671
Patented Sept. 28, 1976

241,671

FLOODLIGHT

Giacinto C. D'Ercoli, Rolling Meadows, Ill., and James P. Kelly, Cudahy, Wis., assignors to McGraw-Edison Co., Elgin, Ill.

Filed Oct. 10, 1975, Ser. No. 621,410

Term of patent 14 years

Int. Cl. D26—03

U.S. Cl. D48—20 K

FIG. 1 is a left front perspective view of a floodlight showing my new design;

FIG. 2 is a right side elevational view thereof;

FIG. 3 is a front elevational view thereof;

FIG. 4 is a rear elevational view thereof;

FIG. 5 is a top plan view thereof; and

FIG. 6 is a bottom plan view thereof.

The lamp is shown in broken lines in FIGS. 1 and 3 for illustrative purposes only.

We claim:

The ornamental design for a floodlight, substantially as shown and described.
